[57] **ABSTRACT**

Genuine leather fabric in the piece comprising a plurality of geometrical sections cut from genuine leather left over scrap, said sections being of selectively predetermined configurations and being secured to each other in end-to-end and side-by-side relation to form a continuous piece which defines said genuine leather fabric in the piece having ornamental characteristics imparted thereto by said secured together sections of predetermined geometrical configuration. The resulting fabric can then be cut in accordance with conventional patterns to form the panels which are assembled and finished into completed articles, such as gloves.

**GENUINE LEATHER FABRIC AND METHOD FOR
MAKING SAME**

RELATED APPLICATION

This is a continuation-in-part of application Ser. No. 767,508 filed Feb. 10, 1977, now U.S. Pat. No. 4,100,623, dated July 18, 1978.

BACKGROUND OF THE INVENTION

The present invention relates to a novel method for making genuine leather piece goods which can then be utilized for the manufacture of a variety of articles, especially gloves.

Genuine leather has so risen in cost and in scarcity as to severely limit the realistic availability of genuine leather as a material for manufacturing articles of wearing apparel and particularly gloves. For example, gloves made of genuine leather which had been available in the past at a relatively reasonable cost and thus within the means of most consumers, have now become luxury items accessible only to the few.

Furthermore, genuine leather is usually not readily susceptible to creative design within the material itself. Thus, most articles made of leather are usually solid in appearance and void of some measure of distinctiveness, therefore reducing the flexibility with which leather can be used in different and exciting ways in connection with the embodiment thereof within articles to be worn by consumers. As a result of this lack of flexibility, though genuine leather articles are rather expensive and often prohibitive, they all look fairly bland in design, with the result that most leather gloves look like each other. Plainly speaking, the leather on these gloves is unicolor and solid throughout the extent of the article.

SUMMARY OF THE INVENTION

It is therefore an object of this invention to provide a new method of making genuine leather piece goods which is far less costly than conventional genuine leather and which is simultaneously more distinctive in appearance, having an inherent ornamental non-bland appearance which is imparted to articles made of such new leather piece goods.

The invention is based in part on the realization that during the manufacture of numerous articles made of genuine leather, there is a great deal of remaining unused leather which is generally referred to as scrap. Such scrap is what is left over from the leather piece goods after there has been cut therefrom the various panels, pursuant to patterns dictated by the design of the particular garment being cut. Thus, for example, the cutting of leather pursuant to patterns relating to a leather jacket article leaves substantial amounts of 55 leather scrap which is generally thought of as being total waste, used in large measure for patching up.

In accordance with the invention, the scraps of left over genuine leather from the conventional cutting operation are utilized to form genuine leather piece goods as contemplated herein. More specifically, these scraps are cut into geometric figures, such as squares, rectangles, or any other type of regular or irregular polygon. These geometric figures are then stitched together to form rows of such figures and a plurality of these rows are stitched in side-by-side relation to define the novel genuine leather piece goods in accordance with the invention.

In stitching together geometrical figures, there can selectively be used such figures of different shades and even of different colors to provide finished piece goods which are highly distinctive and ornamental creating a checkerboard effect heretofore unattainable in genuine leather piece goods. It is also contemplated that different geometrical figures could be combined within one given length of piece goods, for example, rows made of square geometrical figures could be stitched in staggered relation with rows of geometric figures having a rectangular configuration. It will be evident that the variety of combinations is virtually unlimited with the common denominator being the use of individual geometric figures of genuine leather stitched together in some predetermined fashion to create novel genuine leather piece goods heretofore unknown, which goods are particularly suitable for making fashion or work gloves and mittens for conventional, sport as well as industrial use.

BRIEF DESCRIPTION OF THE DRAWINGS

FIG. 1 represents a conventional piece of genuine leather showing the manner in which geometrical figures are cut from left over scrap for forming the novel genuine leather piece goods in accordance with the invention;

FIG. 2 illustrates the manner in which a plurality of square leather sections, cut from scrap, are assembled to form rows;

FIG. 3 is a section taken along lines 3-3 of FIG. 2;

FIG. 4 illustrates the manner in which the rows of FIG. 2 are assembled to form the leather piece goods in accordance with the invention;

FIG. 5 is a section taken along lines 5-5 of FIG. 4;

FIG. 6 illustrates the manner in which a glove blank is obtained from the novel genuine leather piece goods in accordance with one embodiment of the invention;

FIG. 7 illustrates a finished glove obtained with the form as cut in FIG. 6;

FIGS. 8, 9, 10 and 11 illustrate other embodiments of genuine leather piece goods made in accordance with the invention;

FIG. 12 illustrates a finished mitten in accordance with the invention;

FIG. 13 illustrates a set of blanks to be cut from the novel genuine leather piece goods in accordance with another embodiment of the invention;

FIG. 14 illustrates schematically the manner in which the blanks of FIG. 13 are intended to be assembled to form a glove;

FIG. 15 shows a sub-assembly of the blanks of FIG. 14; and

FIG. 16 shows the finished glove made in accordance with the blanks of FIG. 13.

**DESCRIPTION OF THE PREFERRED
EMBODIMENTS**

Referring now to FIG. 1, there is shown a length 10 of genuine leather piece goods and adapted to have cut therefrom panels A and B, which are required in connection with the manufacture of a genuine leather garment. Upon severance of said panels A and B from piece goods 10, there will remain left over genuine leather scrap material 12 for which there has heretofore been no significant use. In accordance with the invention, there is cut from left over scrap 12 as many geometric figures as can be secured from said left over scrap, as for example, squares 14, rectangle 16, and

other possible geometric figures which can be accommodated within left over scrap piece 12. The individual square scrap sections 14 are then stitched together in overlapping relationship, as shown in FIGS. 2 and 3, along lines of stitching 18 to define longitudinal strips 20 made up of a plurality of genuine leather squares.

Thereafter, a plurality of strips 20 are stitched together in overlapping and side-by-side relation along lines of stitching 22 to define genuine leather piece goods 24 as best shown in FIGS. 4 and 5 pursuant to the invention.

Once genuine leather piece goods 24 has been formed in the aforescribed manner, it is essentially used in the same manner as conventional solid leather in the piece for manufacturing articles therefrom. More specifically, newly formed genuine leather in the piece 24 is cut in accordance with predetermined patterns to provide the sections necessary to define a completed article such as a glove.

FIG. 6 illustrates a section of genuine leather in the piece 24 as formed by the above described novel method upon which there is placed a pattern having contour outline 26 which defines the main panel required to form a conventional glove in accordance with one embodiment of the invention. When leather piece 24 is cut along pattern outline 26, the resulting cut section is stitched in the conventional manner after which a thumb section is further stitched at the contour outline of cutout 28 resulting in a finished glove 30 as shown in FIG. 7. It will be noted that finished glove 30 is highly distinctive and attractive in appearance due particularly to the incorporation therein of numerous lines of stitching 32 combining regularity and irregularity to impart to the glove a highly exciting appearance heretofore not available in gloves formed of conventional genuine leather in the piece. At the same time it will be apparent that the glove in all other respects has the same characteristics of gloves made of conventional genuine leather in the piece in terms of the ability of the glove to provide warmth and comfort and to be durable. It will of course be apparent that glove 30, with all the advantages it possesses as described above, can be manufactured at a far lower cost than gloves made of conventional leather in the piece.

It is also evident from the above, without requiring illustration, that the individual square sections 34 forming part of glove 30 need not be of the same shade or even of the same color whereby greater flexibility is available in forming gloves which are highly attractive and exciting and constitute a significant departure from presently available leather gloves.

FIG. 8 illustrates another embodiment 36 of leather in the piece made in accordance with the invention wherein there are provided rows of square sections 38 separated by rows of rectangular sections 40. Such arrangement enables the utilization of leather scrap normally discarded while at the same time participating in the creation of a newly formed genuine leather in the piece having a highly distinctive and ornamental appearance for incorporation in gloves or other articles of wearing apparel to impart thereto similar non-conventional and exciting characteristics.

It will be understood that there is in effect a limitless combination of geometric sections, shades and colors which can be assembled in any desired arrangement as may be conceived, further illustrations of variations being shown at 42 in FIG. 9, at 44 in FIG. 10, and at 46 in FIG. 11.

It will be understood that the gloves as aforescribed embodying the invention can be used as dress fashion gloves, as work gloves for industrial purposes, and as sport gloves. In this connection, it is also understood that instead of gloves, the novel fabric in accordance with the invention could easily be made into mittens, an example of which is shown at 48 in FIG. 12.

Referring now to FIG. 13, there is shown a section of genuine leather in the piece 24 upon which there have been placed four patterns for the purpose of cutting four blanks to be assembled in order to form the glove 50, shown in FIG. 16, in accordance with another embodiment of the invention. In FIG. 13, blank 52 is adapted to form the back portion of the glove, blank 54 is adapted to form the palm side of the glove excluding the two middle fingers but including the thumb, blank 56 is adapted to form the inner edge of the glove and the back side of the thumb, and blank 58 is adapted to form the palm side of the middle fingers for glove 50.

The blanks 52, 54, 56 and 58 are, as cut from genuine leather in the piece 24, shown in FIG. 14 in relative position for their assembly, with the dot and dash lines adjoining the respective contour edges of the blanks which are secured to each other. Thus, edges 60 and 62 of blank 52 are secured to the bottom portions 64 and 66 of slit 68 in blank 54. Such securement causes blank 52 to occupy a folded position in which it defines to palm side of the middle fingers 69 and 70, respectively, as best shown in FIG. 15. Further, the thumb portion 72 is stitched to blank 56 and the latter is stitched to blank 58 to form the sub-assembly of the four blanks in the manner shown in FIG. 15. Finally, the side edges 74 and 76 and the confronting edges of the finger portions are stitched together to produce the completed glove as shown in FIG. 16. The glove 50 when finally assembled in the manner aforescribed is not significantly different in appearance from the glove as shown in FIG. 7, the basic difference between the two being due to the fact that it was formed from different blanks in accordance with different patterns. The net result, however, is a glove which is highly distinctive and attractive in appearance due to the fact that it incorporates therein numerous lines of stitching combining regularity and irregularity to impart to the glove the highly exciting appearance heretofore not available in gloves of conventional genuine leather in the piece. It will be understood that patterns different from those in FIG. 6 or FIG. 13 could be used, so long as they can be appropriately assembled to define a completed glove.

It will also be understood that whereas the genuine leather fabric 24 has been described as being made entirely of genuine leather, it is within the scope of this invention to incorporate in the formation of such fabric, on a regular or irregular basis, some geometrical sections made of material other than genuine leather. Such construction would still retain the highly exciting appearance not formerly available in gloves formed of conventional genuine leather in the piece.

While there is herein shown and described the preferred embodiments of the invention, it will be understood that the invention may be embodied otherwise than as herein specifically illustrated or described, and that in the illustrated embodiments certain changes in the details of construction and in the form and arrangement of parts may be made without departing from the underlying idea or principles of this invention within the scope of the appended claims.

Having thus described my invention, what I claim and desire to secure by letters patent is:

1. A genuine leather glove comprising a plurality of single layer, unsupported geometrical sections cut from genuine leather left over scrap, said sections being of selectively predetermined configurations and being secured to each other in overlapping end-to-end and overlapping side-by-side relation to form a continuous piece having ornamental characteristics imparted thereto by said secured together sections of predetermined geometrical configuration, said piece being cut into a plurality of blanks assembled together to define a conventional glove having a palm side, a back side, four discrete finger stalls and a thumb stall, whereby the entire glove has imparted thereto the ornamental char- 10 15

acteristics of said continuous piece, each of said blanks including a plurality of said unsupported geometric sections secured to each other in said overlapping relation.

2. A genuine leather glove in accordance with claim 1, wherein said plurality of blanks comprise the following:

- a. a blank forming the back portion of the glove;
- b. a blank forming the palm side of the glove not including the middle fingers but including the thumb;
- c. a blank forming the inner edge of the glove and back side of the thumb; and
- d. a blank forming the palm side of the middle fingers.
